(57) **CLAIM**

We claim the ornamental design for the pocket with hand strap, as shown and described.

DESCRIPTION

FIG. 1 is a front perspective view of the pocket with hand strap, showing our new design.

FIG. 2 is a rear perspective view of the pocket with hand strap.

FIG. 3 is a front view of the pocket with hand strap.

FIG. 4 is a right side view of the pocket with hand strap, the left side view being a mirror image.

FIG. 5 is a top view of the pocket with hand strap.

FIG. 6 is a bottom view of the pocket with hand strap; and, FIG. 7 is a rear view of the pocket with hand strap.

Features shown in broken lines depict environmental structure and form no part of the claimed design.
